Stephen M. Long

Letters Patent

The Schedule referred to in these Letters Patent, and making part of the same, containing a description in the words of the said S. M. Long himself, of his improvement in the Locomotive Steam-Engine and other Rail-Road carriages.

I. The application and use of two parallel cylindrical boilers placed horizontally on the carriage and lengthwise thereof with one or more horizontal flues passing longitudinally through each boiler in the lower half thereof, which flues must be of a size sufficient to convey the heated air, flame &c from the fire place to the chimney both of which, in this case, are situated at the same end of the boilers.

The fire place is located beneath the boilers and has its side and front frames of sheet iron suitably lined or coated with fire brick or clay and in the rear sides above a bridging of brick or rough stone and opens into a broad flue of the entire width of the boiler, the side bottom and back ends of which are constructed of sheet iron suitably faced and appropriately lined or coated with fire brick or clay. The boilers themselves constitute the roof or upper side, not only of this broad flue but also of the fire place at the back end of the boiler. The broad flue communicates with the flues leading through the boiler. This mode of construction is believed to be entirely new in its application to Locomotive Steam Engines.

In this item I claim the application of two horizontal cylindrical boilers with two or more flues in each passing longitudinally through them the fire place being anterior of the boilers & beneath them a single boiler of similar construction having ^{therm} previously employed by Oliver Evans in the construction of a Locomotive Engine and by others for other purposes.

II. The application and use of three parallel cylindrical boilers placed horizontally on the carriage and lengthwise thereof with one

Dec 28, 1832

without flues leading through them. the latter made being prepared when the diameter of each boiler does not exceed fifteen inches. The fire place in this range also is located at one end of the boilers & occupies a width equal scarcely to that of the three together. The front and sides of the fire place are formed of sheet iron appropriately braced and stiffened and lined with fine brick or clay as before. In rear of the fire place is a bridging of brick or soap stone as before mentioned above which the fire place commences with a broad flue of appropriate depth & of a width equal to that of the fire place or to the entire width occupied by the three boilers. The sides bottom and rear of this flue are constructed of sheet iron or copper and appropriately lined with fine brick or clay. Its roof is formed of the three boilers which have their entire under surface or those portions of their entire surface situated below a horizontal plane passing through their centers exposed to the action of the heat generated in the fire place.

The middle boiler of the three is shorter by about one foot than either of the outside boilers in order to afford a communication from the broad flue into the chimney which rises perpendicular from the back or rear end of the middle boiler & between the other two boilers.

A direct passage from the flue into the chimney is intercepted by a tile of fine clay or slab of soap stone which compels the heated air to pass round the extremities of the tile and immediately under the back ends of the exterior boilers before it can enter the chimney which rises immediately back of the tile. For many particular in regard to the relative dimensions of the grate and the best mode of conducting furnaces for steam engines I am indebted to the liberality and intelligence of James Watt Esq; of Philadelphia. but their application and use in the construction of locomotives, engines, & claim for myself as new and useful. By this claim I claim the application of three horizontal cylindrical boilers (with or without flues leading through them) the fire place being situated of the boilers and beneath them. similar boilers having been previously employed by myself.

Dec 28, 1832 23

and others for other purposes. I also claim the manner of construction adopted in the item - although as stated before I am indebted to Mr. Knibb for much useful information which enabled me to regulate the dimensions of the various parts as exhibited in the Pennsylvania Locomotive.

III. Another mode of constructing a switch or movable chimney & its application to Locomotive Steam Engines which is as follows. Viz. The chimney rises in a square form through the space provided for it as stated in the preceding item of this supplement to the height of two or three feet above the upper edge of the tile or stone stone slab before mentioned. This portion of the chimney is sufficiently large to receive a lining of fire clay to protect it against the heat and serves as a pedestal or basement for the switch or movable part of the chimney - which is round and is connected with the pedestal by means of a hinge or joint on which this part of the chimney to swing in such a manner as to admit of its being laid horizontally upon the carriage or erected perpendicular as occasion may require in passing under Bridges through tunnels &c.

IV. The waste steam of the working cylinder is conveyed by a tube or pipe into the basement of the chimney into which it is injected perpendicular from the tube in order to increase or accelerate the draft through the fire place flue and chimney.

I claim in this item the application of a movable or switch chimney differing from that described in the 4th item of my Specification of June 1831. in having but a single oscillating joint instead of two lateral joints as specified in that instrument. V. An apparatus intended as a substitute for the force pump of ordinary Engines and for the purpose of supplying the boiler of locomotive & other Steam Engines with water. which apparatus I shall designate by the appellation of ^{the} pump. inasmuch as it is calculated to perform the functions of a supply pump without the aid of any external force except in so far as it may be useful in the burning of coals - The pump consists of a hollow cylinder capped at both ends and made steam tight to be located

DEC 28, 1832

in such a position that the lowest part of its cavity shall be elevated at least as high as the upper surface or greatest height of the water in the boiler, to which the pump is attached. The lowest part of the pump or cylinder must communicate with the boiler at a point or points below their water surface; by means of a pipe or tube of suitable size furnished with a stop cock or valve denominated the supply cock which may be opened or shut at pleasure. The uppermost part of the pump or cylinder must also communicate with the boiler at a point above their water surface by means of a tube or pipe (which may be considerably smaller than the former) furnished with a cock or valve to be called the steam cock by means of which tube and cock steam from the boiler may be conveyed into the pump at pleasure. The pump must also communicate with the water cock tank or reservoir by means of a tube pipe or hose furnished in like manner with a stop cock or valve to be called the draft cock for the purpose of opening & shutting this communication at pleasure. Moreover a small cock or valve to be called the ejection cock must be applied to the pump in some convenient position for the purpose of discharging the steam from the pump whenever there is occasion to refresh it with water. The steam thus discharged may be conveyed ^{through} a pipe to the steam chest attached to the working cylinder, instead of being wasted may be made to contribute to the operation of the engine. — The operation of the fore pump is as follows.

1st. — Let the supply cock and steam cock be shut — open the ejection cock and also the draft cock and the water will freely flow from the reservoir (which is supposed to be higher than the Pump) into the pump. When the Pump is — full of water or sufficiently so, shut the ejection and draft cocks and then open the steam cock and afterward the supply cock and the water will flow as freely from the Pump into the boiler through the supply tube its place in the pump being occupied by steam from the boiler. The operation may

7351X

Dec 28, 1832 23

be repeated at pleasure by shutting again the cockes last mentioned and opening the others. — The principle on which this pump operates was verbally explained to me by Charles Hetherill, Esq. of Philadelphia early in the summer of 1831. Its manner of construction and its application to Steam Engines, and especially its use in locomotive Steam Engines. It was new and original with myself. — The free pump may be surrounded by a casing in a cylindrical form and of such size as to admit a space of one inch around between the casing and the pump on all sides. Into this space the waste steam from the working cylinder of the engine may be conveyed and from which it may also be conducted into the chimney by means of suitable tubes or pipes communicating between these several parts. The water in the pump may then be heated by the waste steam and boiler prepared for injection into the boiler. While the water formed in the casing from the condensation of steam may readily be conveyed to the reservoir in the manner herein after explained. In this item I claim as new and original not only the construction of the free pump as described in this item, but also its application and use in Steam Engines generally and in connection with Steam generators, as a means of supplying them with water, especially its application to locomotive Steam Engines.

X. 5th In order to dispense with the bell crank and other appendages necessary to their use. I have substituted a compound axle in three parts, with cranks and other appropriate parts, in connection with the working wheel of the locomotive. This arrangement is effected in part by adopting in frame, wheel, of different diameters and by providing suitable bearings, for the support of the carriage bed, boiler, cylinder, &c both externally and internally of the wheel, the working wheel being about 4 $\frac{1}{2}$ feet and the others about 3 feet in diameter with rims respectively adapted to a road with curvature on a radius of 400 feet. The arrangement here attended

Dec 28, 1832

to together with the leading improvements contemplated in this application are ready to be exemplified in the model deposited in the Patent Office.

VI. 6th. A method of heating the water within the fire Pump, by means of the waste steam and of preventing from the water being condensed upon the steam by intercepting its drainage and by passage from the fire Pump into the chimney or atmosphere.

This method consists in the injection of the waste steam first into the pump by which the pump is suspended. This is done by a stone, a sort of dome attached to the upper part or side of the casing into which dome the steam enters through a tube rising from the lower part of the cavity of the casing, passing outwardly through the fire pump, and punctuating nearly to the top of the stone and then entering into the chimney or open air through a tube passing out of the stone at a point about midway between its top and bottom. The water that may have been formed by condensation and collected in the lower part of the casing will thus be carried upward by the steam through the vertical tube under pressure of the pump and be deposited in the stone, whence it will be conveyed through a tube leading from the bottom of the stone and thrown into the chimney for future use.

VII. A further method of constructing wheels for locomotives, &c, and other rail way Carriages, differing from that described in the first sheet of my Specification of Nov 11, 1831, in the following particular, viz. The rim together with its flanges is cast separately from the hub and spokes and is furnished with washers adapted to the reception of the outward webbing of the spokes, which the latter are inserted and held fast by means of screwable or clamp, embracing the ends of the spokes and compressing them to the outer flange of the rim. The spokes have a taper from becoming round as they recede from the hub. All other respects the spokes and hub may be similar to those of the wheel described in my Specification of Nov 11, 1831, before alluded to. The mode

735IX

Dec 28, 1832 239

of constructing Wheels for Rail-Road Cars is believed to be entirely new and will be exemplified in this model intended as an illustration of these very improvements.

Among the benefits resulting from this improvement are the following namely. - The hub of the above-mentioned wheel may be made of such iron as is best calculated to facilitate the construction of the wheel without impairing its strength or durability, for example the iron may be made upon hardened steel which the spokes shall admit of being much lengthened in order that their proper adjustment may be made of iron much softer and more susceptible of being wrought with ease and dispatch. The iron may be case hardened or cast in a shell without of reducing an injurious strain upon this or any other part of the Wheel thereby impairing its efficient strength. - When the iron shall have been cast, this may effectually be renovated by substituting a new iron in connection with the old spokes, and hub, which upon the nature of the service they have to perform are far less exposed to strain than the iron. By this means the service of the Wheels of Rail-Road Carriages may be effected at a comparatively moderate expense.

VIII. 8th. The successful application and use of Anthracite coal as fuel for the generation of steam for the propulsions of Locomotive Engines and the towing of loaded cars, continuously for more than one hour at a speed often or more miles per hour. The weight of the entire train and load being equivalent to but little more than the weight of the Engine and the rail road being level or at a less pitch the weight of the load being proportionably increased.
